[57] CLAIM

The ornamental design for a flash unit for a photographic camera, as shown and described.

DESCRIPTION

FIG. 1 is a front perspective view of a flash unit for a photographic camera showing my new design.

FIG. 2 is a rear elevational view.

FIG. 3 is a side elevational view as seen from the left of FIG. 1.

FIG. 4 is a front elevational view.

FIG. 5 is a side elevational view as seen from the right of FIG. 1.

FIG. 6 is a top plan view.

FIG. 7 is a bottom plan view.

FIG. 8 is a front perspective view with the mounting clip rotated 90° from its position as shown in FIGS. 1 to 7.

*Fig. 1**Fig. 2**Fig. 3**Fig. 4**Fig. 5*
